Primary Examiner — Brett Miller(74) *Attorney, Agent, or Firm* — Jonathan R. Smith**CLAIM**

I claim the ornamental design for a grilling utensil, as shown and described.

DESCRIPTION

FIG. 1 is an oblique view of the invention;

FIG. 2 is the top view thereof;

FIG. 3 is the right side, left side, and rear view thereof; and, FIG. 4 is the bottom view thereof.

The intended use of this invention is to provide a decorative grilling utensil on a grill.
